Specification for Design.

Patented Nov. 15, 1921.

Application filed August 22, 1921. Serial No. 494,442. Term of patent 14 years.

To all whom it may concern:

Be it known that I, THORNTON F. MILLER, a citizen of the United States, residing at Pittsburgh, in the county of Allegheny and State of Pennsylvania, have invented a new, original, and ornamental Design for a Badge, of which the following is a specification, reference being had to the accompanying drawing, forming part thereof.

The drawing shows the badge, the subject matter of the present invention, in front elevation.

What I claim is:

The ornamental design for a badge, substantially as shown.

In testimony whereof, I hereunto set my hand.

THORNTON F. MILLER.
